COMBINED MUFFLER AND HEATER

Emmet P. Gray, Detroit, Mich.

Application January 2, 1937, Serial No. 118,775

7 Claims. (Cl. 257—16)

My invention relates to improvements in a combined muffler and heater for connecting with the exhaust conduits of internal combustion engines and similar units, and also with passenger or body compartments to be heated, and the objects of my improvements are, first, to provide a combined muffler and heater mechanism that will cool exhaust gases or fluids passing therethrough and heat a flow of air or fluid passing therethrough; second, to provide a muffler mechanism having a cooling element or member located between inlet and outlet openings of the muffler mechanism; third, to provide a heater element having means for guiding hot gases or fluids to flow therethrough and therearound; fourth, to provide a muffler mechanism adapted to cause exhaust fluids or gases to flow with a whirling motion into and around a heater element; fifth, to provide a combined muffler and heater mechanism having a corrugated walled heater element installed in a tubular member to provide passages for the flow of exhaust gases or fluids therethrough between the tubular member and the heater element; sixth, to provide a heater element provided with heated baffle means for guiding a cooling fluid to more efficiently flow through the heater element for the purpose of absorbing heat; seventh, to provide a muffler mechanism with a heater element having a cone shaped passage for partially impeding the flow of exhaust gases or fluids therethrough to enable the heater element to more efficiently absorb heat for increasing the temperature of a cooling element flowing therethrough; eighth, to provide a combined muffler and heater member with means for controlling the flow of a cooling fluid therethrough to absorb heat and to flow either to a compartment to be heated or into the atmosphere; ninth, to provide a heater mechanism with means for inducing a flow of cooling fluid therethrough; tenth, to provide a heater mechanism with a scoop member for facilitating a flow of cooling fluid therethrough; eleventh, to provide a heater element in a muffler mechanism and having a through passage for the passage of exhaust gases or fluids; twelfth, to provide a heater element in a muffler and adapted for the flow of exhaust gases or fluids therearound with means for directing the flow of the gases or fluids toward the center of the muffler and the outlet of the muffler with a whirling motion; thirteenth, to provide a new method of heating a compartment of an automotive vehicle or similar unit; fourteenth, to provide a muffler or heater means provided with insulation means; fifteenth, to

provide a heater means which when used by itself will provide a muffling operation; and sixteenth, to provide a heater means with a valve mechanism for controlling a flow of air so that all, or a part of none, of said flow of air may be guided through or past the heater means as desired.

I attain these objects by the mechanism illustrated in the accompanying drawings, in which:—

Figure 1 is a longitudinal section of the combined muffler and heater taken in a vertical plane through its axis; Fig. 2, a sectional view of my combined muffler and heater assembly taken on the line 2—2, Fig. 1; Fig. 3, a sectional view of my muffler and heater assembly taken on the line 3—3, Fig. 1; Fig. 4, a side elevation of the heater housing or element; Fig. 5, a sectional view of the combined muffler and heater taken on the line 5—5, Fig. 1; Fig. 6, a partial sectional view of the combined muffler and heater assembly taken on the line 6—6, Fig. 1; Fig. 7, a diagrammatic view disclosing the combined muffler and heater assembly connected with a ventilator mechanism located in a passenger or body compartment of an automotive vehicle, together with means for inducing a draft or flow of air through the heating housing or element of the combined muffler and heater assembly; Fig. 8, a partial side view of the combined muffler and heater assembly connected with an exhaust pipe or conduit of an internal combustion engine or similar unit; Fig. 9, a view disclosing power driven fan mechanism for inducing a draft or flow of air through the combined muffler and heater assembly; Fig. 10, a partial sectional view of the combined muffler and heater assembly taken on the line 10—10, Fig. 1; Fig. 11, a longitudinal section through a modified design of my combined muffler and heater, said longitudinal section being taken in a vertical plane through its axis; Fig. 12, a sectional view of the combined muffler and heater assembly taken on the line 12—12, Fig. 11, said sectional view being drawn to a larger scale than that of Fig. 11; Fig. 13, a side elevation of the heater housing or element of the combined muffler and heater assembly disclosed in Fig. 11; Fig. 14, an end view of the heater housing or element disclosed in Fig. 13; Fig. 15, a sectional view of the heater housing or element disclosed in Figs. 13 and 14, said sectional view being taken on the line 15—15, Fig. 13; Fig. 16, a side view of the two way connection member disclosed in the combined muffler and heater assembly of Fig. 11; Fig. 17, a side view of one of the lock nut members utilized in the combined muffler and heater.

assembly of Fig. 11; Fig. 18, an end view of the lock nut member disclosed in Fig. 17; and Fig. 19, an enlarged partial sectional view of the shell of the muffler and its envelope of insulation or packing material together with its outer envelope or covering, said enlarged partial sectional view being taken on the line 19—19, Fig. 12.

It is to be noted that my muffler and heater assembly comprises portions of my muffler mechanism disclosed in my pending application for United States Letters Patent for Muffler, Serial No. 51,779, filed November 27, 1935, together with a heater housing or element installed therein as more fully described hereinafter.

15 The tubular member or assembly A comprises a tubular member 4 which is provided with a plurality of rows of louvered perforations 2 each provided with a hooded portion 3 formed by displacing a portion of the wall portion 20 of the tubular member 4 to guide the flow of gases through the louvered perforations 2 to flow tangentially around the outside surface of the tubular assembly A and around the inside surface of the outer tube or housing 4, the rows 25 of louvered perforations 3 being arranged in rows circumferentially around the tubular assembly A, the assembly A being provided with the substantially straight cylindrical portion 5 of reduced diameter at its rear end and which forms the 30 outlet portion of the tubular assembly A, the straight cylindrical portion 5 being connected with the main wall portion of the tubular assembly A by the conically shaped or frusto-conical portion 6.

35 The tubular assembly A may be constructed by forming a piece, strip, or sheet of material into a cylindrical tube having the slot 7 extending longitudinally thereof in a similar way to that disclosed in the above entitled pending application 40 for Muffler, the tubular assembly A extending at its front end beyond the end of each portion of the outer tube 4 to form the inlet portion 8 of the combined muffler and heater assembly, the inlet portion 8 being sized to fit larger or smaller diameters of exhaust pipes connected with internal combustion assemblies or similar units.

The plate or disc member 9 is provided with the cylindrical flange 10 which is adapted to engage and fit within the inner surface of the outer tube 4 and to be secured thereto as by spot welding or similar means, the disc member 9 being further provided with the flange 11 which is provided with the bore 11A through which extends the tubular assembly A, the disc member 9 closing the front end of the outer tube 4 between the tubular assembly A and the outer wall portions of the outer tube 4 in a similar way to that disclosed in the above mentioned pending application.

60 The plate or disc member 12 is provided with the cylindrical flange 13 which is adapted to engage and fit within the inside surface of the outer tube 4 and may be secured thereto as by spot welding or similar means, the disc member 12 being further provided with the flange 14 which is provided with the bore 14A which is adapted to engage the hood portions 3 of the louvered perforations 2 and to support the rear portion of the tubular assembly A, thus not only providing an additional support for the tubular member or assembly A to relieve the front end portion of the tubular assembly A which is supported in the disc member 9 from excessive stresses due to connection with the exhaust pipe of internal combustion engines or similar units, but also as

shown in Fig. 10 provides a plurality of openings 15 between the inner surface of the bore 14A and the hood portions 3 of the louvered perforations 2 to permit the exhaust gases to flow slowly from the chamber 16 through the plurality of openings 15 into the chamber 17 in a manner similar to that disclosed in the above mentioned pending application.

The combined muffler and heater assembly is also provided with a disc or plate member 18 at its rear portion, said disc member 18 being provided with the cylindrical flange 19 which is adapted to engage and fit within the inner surface of the outer tube 4 and to be secured thereto as by spot welding or similar means, the disc member 18 being further provided with the flange 20 which is provided with the bore 20A extending therethrough, the bore 20A being engaged by and adapted to support the front end of the tubular assembly B, the front end of the tubular assembly B being located substantially flush with the main wall portion of the disc member 18.

The tubular assembly B is similar to the tubular assembly A, above described, and is provided with the plurality of rows of louvered perforations 2 together with the hooded portions 3 and the substantially straight cylindrical portion 5, of reduced diameter, and connected to the main wall portion of the tubular member or assembly B by the conically shaped or frusto-conical portion 6.

It is to be noted that the tubular assembly B is mounted in axial alignment with the tubular assembly A and will be supported by the disc member 18 in conjunction with the disc member 21 which is provided with the cylindrical flange 22 for fitting with and engaging the inner surface of the outer tube 4 and is adapted to be secured thereto by spot welding or similar means, the disc member 21 being further provided with the flange 23 having the bore 23A therethrough for engaging the hooded portions 3 of one of the rows of louvered perforations 2 in a similar way to that in which the tubular assembly A is supported by the disc member 12, the bore 23A and the hooded portions 3 forming a plurality of openings 15 to permit the exhaust gases to flow slowly from the chamber 25 into the chamber 26, this construction being similar to that disclosed in the above mentioned pending application.

Also the combined muffler and heater assembly comprises the disc member 27 which is provided with the cylindrical flange 28 which is adapted to engage and fit with the inner surface of the outer tube 4 and to be secured thereto as by spot welding or similar means, the disc member 27 being further provided with the flange 29 which extends outwardly in the same direction as the cylindrical flange 28 from the main wall portion of the disc member 27, the flange 29 being provided with the bore 29A which engages and supports the relatively short outlet pipe or tube 30 which thus provides a passage for the gases to flow out of the combined muffler and heater assembly into the atmosphere, this construction also being similar to that disclosed in the above pending application.

It is also to be noted that the tubular assembly B will be of smaller diameter than the tubular assembly A and if desired the exhaust pipe or tube 30 may be of smaller diameter than the tubular assembly B.

The housing or member 31 is preferably made of cast material and is provided with a plurality of corrugations, convolutions, or fluted portions

32 formed in its outer wall portion. The maximum diameter or dimensions of the corrugated or fluted structure will be of sufficient size to telescopically fit within and engage the inner surface of the outer tube 4, the extreme outer semi-cylindrical surfaces 33 being adapted to engage the inner surfaces of the outer tube 4 by a light press fit, the corrugated or fluted structure 32 providing a plurality of openings or 10 passages 34 extending longitudinally between the outside surfaces of the corrugations and the inner surfaces of the outer tube 4 to permit the exhaust gases to flow therethrough as more fully described hereinafter.

15 The corrugated wall structure of the housing 31 is extended at the front end of the housing 31 to form the wall portions 35 which extend substantially at right angles to the axis of the muffler assembly, the wall portions 35 being extended to form and connect with the conical or frusto-conical shaped wall portion 36 which extends longitudinally through the housing 31 and connects at its rear or outlet end with the wall portion 37 which extends substantially at right angles to the axis of the combined muffler and heater assembly and connects with the opposite end of the corrugated structure 32. Thus the housing 31 is provided with the cone shaped passage 38 extending longitudinally therethrough together with the chamber or passage 39 which extends circumferentially around the wall portions of the conical shaped passage 38, the chamber 39 being closed relative to the conical shaped passage 38.

35 The housing 31 is further provided with a plurality of fins or webs 40 which are located to extend tangentially outward from the circle, indicated as being located adjacent and around the outlet opening of the cone shaped passage 38 and extending from the circle or diameter 41, to points located substantially at the center of the rear end of the fluted portions or passages 34 of the corrugated structure 32 to guide or direct fluids or gases which flow adjacent the wall portion 37 to progress toward and into the tubular assembly B with a whirling or turbulent motion as more fully described hereinafter.

50 The housing 31 is also provided with the boss portion 42 which is provided with the opening or passage 43 extending therethrough substantially at right angles to the axis of the combined muffler and heater assembly to connect the outside surface of the housing 31 and the chamber 39, the opening or passage 43 being threaded to engage the nipple or connection member 45 which is thus mounted in the boss portion 42 of the housing 31 and extends through suitable openings in the outer tubular member 4 and beyond the outer wall portions of the outer tube 4.

60 The housing 31 is also provided with the boss portion 44 which is provided with the opening or passage 46 extending therethrough substantially at right angles to the axis of the combined muffler and heater assembly to connect the outside surfaces of the housing 31 with the chamber 39, the opening or passage 46 being threaded to engage the nipple or connection 47 which extends through the boss portion 44 and through a suitable opening in the wall portion of the outer tube 4 and beyond the outside wall portion of the outer tube 4.

65 It is now to be noted that the housing 31 is located and positioned between the inlet and outlet openings of the combined muffler and heater assembly and may be firmly secured in said por-

tion by the nuts 48 and 49 which threadably engage the nipples 45 and 47 to clamp the washers 50 and 51 against the outer wall surface of the outer tube 4, the washers 50 and 51 being formed with the flange portions 52 and 53 to conform with the shape of the outer wall surfaces of the outer tube 4.

70 Fig. 8 discloses the inlet portion 8 of my combined muffler and heater assembly connected with the end of an exhaust pipe 24 which is adapted for connection with the exhaust manifold or mechanism of an internal combustion engine or similar unit, the end of the exhaust pipe 24 extending within the inlet portion 8, the inlet portion 8 being clamped or contacted by the clamp member 54 to fit snugly with the exhaust pipe 24, the clamp member 54 being provided with spaced lug or ear portions 54A which may be clamped by the bolt 54B.

75 Also the nipple or connection 45 as disclosed in Fig. 7, is threadably connected with the two-way connection 55 which is provided with the extension portion 56 in which is mounted the valve member 57 which is revolvably supported by the shaft 58 which is provided with the lever member 59 having a forked end for receiving the cable or rod member 60 therethrough, said cable or rod member 60 being adapted to extend to a convenient position adjacent the driver of a motor vehicle to permit the manual operation of the rod 60, together with the valve mechanism, the cable 60 being enclosed in the conduit or tube 60A when the cable 60 is of the flexible type.

80 Also the two way connection 55 is provided with the extension portion 56 in which is mounted the valve member 62 which is rotatably supported by the shaft 63 to which is connected the lever 64 which is also provided with a forked end for connection with the rod or cable 60 which is provided with the collars or shouldered portions 60B for engaging the levers 59 and 64 to enable the cable or rod 60 to operate the levers 59 and 64.

85 The tube or pipe 66 which may be of either rigid or flexible construction, extends within the passage 67 of the two way connection 55 and also extends within the passage 68 of the ventilator or grill housing 69 which is provided with a suitable flange portion 70 to permit the grill housing 69 to be secured to the floor boards 71 of the passenger or body compartment of an automotive vehicle, the flange portion 70 being secured to the boards 71 by the screws 73, the grill housing 69 being partially closed at its upper end by the grid or register mechanism 74 which may be manually operated to an open or closed position to allow the heat developed in the combined muffler and heater assembly to pass or flow upwardly through the two way connection member 55, through the pipe or tube 66 and through the ventilator or grill 70 housing 69 and out through the grid or register member 74.

90 When it is desired not to utilize the heat developed in the combined muffler and heater mechanism for heating the body or similar portion of the automotive vehicle, such as in the summertime and at other times, the valve 57 may be operated to a closed position and in a similar way, the valve 62 may be operated to an open position to allow the heat to pass out into the two way connection member and out through the passage of the extension portion 56, past the valve 62 and out to the atmosphere, and in a similar way the valve 62 may be closed in cold weather and the valve 57 may be opened to provide for a flow 75

of heat, fluid, or air from the combined muffler and heater assembly into the desired compartment of an automotive vehicle or similar unit.

Fig. 7 discloses a diagrammatic or assembly view of the combined muffler and heater assembly provided with a scoop member 76 which is threadably supported on the nipple member 47 and is provided with a bell mouthed opening or inlet end 77 which is adapted to be located in a position where the bell mouthed end 77 will tend to scoop in cold air when the automotive vehicle is travelling so that the flow of air will pass through the bell mouth end 77 and through the scoop member 76, through the passage of the nipple 47 into the chamber 39 to provide means for operating a flow of cold air through the heater element or housing 31 and after being heated to the desired compartment of an automotive vehicle or similar unit.

Also if it is desired to obtain a greater flow of cold air through the housing 31 than is possible by means of the scoop member 76 or by a natural flow of cold air through the nipple 47, a means for propelling or drawing the air through the nipple 47 may be utilized, such as the fan member 78 which is electrically connected with and operated by the electrical motor 79, said fan member being installed between the combined muffler and heater assembly and the ventilator or grill housing 69 to provide a forced draft or drawing of the air through the housings 31 and 69, disclosed in Fig. 7, or the ventilator or grill member 80 may be connected to the tube or conduit 66 and mounted on a dash or similar member 81 of a vehicle, the housing 82 enclosing the fan member 78 and electrical motor 79, the housing 82 being provided with an opening 83 through which the heated air or fluid may pass into the desired compartment.

It is also to be noted that the housing 31 is provided with the oppositely disposed webs or ribs 84 connected between oppositely disposed sides of the conical portion 36 and the inside surfaces of the outer wall portions of the housing 31, the rib or webs 84 extending for a portion only of the inside length of the housing 31 to form passages or openings 85 between the rear edge of the web or rib portions 84 and the wall portion 37, the location of the rib or web portions 84 also forming the passages or openings 86 between the forward edge of the webs or ribs 84 and the inside surface of the wall portion 35, the ribs 84 acting as baffle means for causing the cooling fluid or air, passing into the chamber 39, to flow longitudinally of the ribs 84 and into the conical shaped wall structure 36.

It is also to be noted that whereas I refer to the housing 31 and its assembled parts as a heater member, it is to be understood that this mechanism also constitutes a cooling member or element inasmuch as it will tend to cool the fluids or gases flowing through the combined muffler and heater assembly from the exhaust pipes or conduits of an internal combustion engine or similar unit, and at the same time the mechanism comprising the housing 31 and its connected parts will tend to increase or heat up the cold air flowing through the nipple 47 into the chamber 39 of the housing 31 and thence through the nipple 45 into and through the ventilator or grill mechanism into the desired passenger or body compartment of the vehicle. However, to simplify the specification, I refer to the housing 31 and its connected parts as a heater element and it will be thus understood that it performs a cooling as well as a

heating operation or function and also when used by itself as a muffler function.

In the combined muffler and heater assembly disclosed in Fig. 11, the tubular assemblies A and B are similar to those disclosed in Fig. 1, the tubular members of the tubular assembly A and the tube 30 each being disclosed with a relatively short slot 1A at its inlet or outlet portion.

It is to be noted that the tubular assembly A in Fig. 11 is disclosed as being solely supported at its front portion by being suitably secured in the bores 11A of the flanges 11 of the disc members 9A, it being understood that additional support means may be provided for the tubular assembly if desired. The disc members 9A are assembled adjacent one another to form the chamber or space 90 which contains the insulation or packing 91A which is constructed of asbestos, fibre or similar material having heat insulating characteristics.

It is to be noted that the inner tube or housing 91 is secured to the flanges 10 of the discs 9A and forms the shell of the muffler assembly, the inner tube or housing 91 being covered and surrounded by the layer or envelope of insulation or packing 92 which is constructed of asbestos, fibre or similar material having heat insulating characteristics.

The combined muffler and heater assembly of Fig. 11 is provided with the disc members 18A, 21A and 27B similar to the disc members 18, 21 and 27 of Fig. 1, the disc members 18A, 21A and 27B being provided with flanges 20B, 23B, and 29B respectively having bores 20A, 23A and 29A for engaging and supporting the tubular assembly B, the disc members 27B, however, being utilized in pairs to provide the chamber or space 94 for containing the insulation or packing 95.

The housing 96 in Fig. 11 is similar to the housing 31 of Fig. 1 and fits within the inner tube or housing 91 and has its corrugated wall structure extended to form the wall portions 97 which connect with the wall portions which form the cylindrical portion 98 which connects with the conical or frusto-conical portion 99 which connects with the straight portion 100 connected with the wall portion 101, the straight portion 100 having the opening or passage 102 which forms the rear or outlet end of the housing 96. Thus the housing 96 is provided with the chamber 103 which conforms to the outer shape of the tubular assembly A extending therewithin and provides a clearance space therearound, the housing 96 being further provided with the chamber 104 which is provided with boss portions 105 in which are mounted the bushings 106 and 107 which may be secured therein as by threading, pressing or similar means, the bushings 106 and 107 having respectively the passages 108 and 109 connecting with the chamber 104 at points oppositely disposed about the conical or frusto-conical portion 99.

The washer or bushing members 110 are provided with flanges 111 which are shaped to conform with the outside diameter or shape of the outer cover or tubular member 93 and are provided with openings or passages through which extend the bushings 106 and 107 which are adapted to hold the washer or bushing members 110 in position to prevent leakage around the bushing members 106 and 107 and to locate the housing 96 and its connected parts in the muffler assembly.

The bushing members 106 and 107 thus extend

through suitable openings in the inner tube 91, the insulation or packing 92 and the outer cover or housing member 93, and by their connection with the boss portions 105 of the housing 96 5 clamp the bushing members 110 in place and by threadable or similar connecting means respectively support the two way connection members 112A and 112 which are respectively provided with extension portions 113 and 114 which extend 0 within and respectively engage the bushing members 106 and 107.

The two way connection member 112A is similar to the member 55 of Fig. 7 and is provided with extension portions 56 and 65 in which are 15 mounted valve members 57 and 62, the two way connection member 112A being provided with the rivets or similar members 115 which are adapted to form stops for tubular members when mounted in and connected with the extension 20 portions 56 and 65 for guiding the heated air to portions of the vehicle or similar units by means of a tube or pipe 66 as disclosed in Fig. 7.

The valve members 57 and 62 are respectively 25 rotatably supported on shafts 58 and 63 which are respectively provided with lever members 116 and 117 which extend upwardly from the shafts 58 and 63, as disclosed in Fig. 16, the lever members 116 and 117 each being provided with boss portions 118 which are pivotally connected by 30 the cable or rod member 119, the lever member 116 being further pivotally connected with the cable or rod member 120 which is adapted to extend to a convenient position adjacent the driver of the motor vehicle to facilitate manual operation 35 thereof.

The two way connection member 112 is provided with the extension portions 121 and 122, the extension portion 121 being provided with a bell mouthed end or inlet 123 which will tend to scoop 40 in cold air when the automotive vehicle is traveling.

The valve member 124 is rotatably supported 45 on the shaft 125 and is adapted to engage the seat surface 126 to close the passage 127 and prevent cold air from passing thereto when the passage 128 is in its closed position, as disclosed by full lines, the shaft 125 being provided with the lever member 129 which is connected with the cable or rod 50 member 130 which is adapted to extend to a convenient position adjacent the driver of the motor vehicle to facilitate manual operation thereof. When the valve member 124 is in its open position, as disclosed by the dotted lines 55 131, Fig. 11, cold air is allowed to pass into the passage 127 and through the combined heater and muffler assembly, the cold air then being prevented from passing into the flexible tube 132 which may be positioned to guide the cold air 60 where desired when the cold air is guided thereto by movement of the valve member 124 away from the position indicated by the dotted lines 131.

It is to be noted that the two way connection 65 member 112A and its valve mechanism can be used without the two way connection member 112 in place of which a scoop or similar cold air inlet member 76 may be used in place thereof. Also it is to be noted that with the use of the 70 two connection member 112A the heated air may be discharged into the open or outside atmosphere or the heated air may all or partially be passed into the automotive vehicle, thus cooling the combined heater and muffler all the year 75 around.

Also the two way connection member 112 and its valve mechanism may be used without the two way connection member 112A and with its valve member 124 open or partially open will guide and force all or part of the cold air into and 5 through the combined heater and muffler assembly as desired.

The housing 96 is provided with the oppositely disposed webs or ribs 133 connected between oppositely disposed sides of the cylindrical portion 10 98 and the conical or frusto-conical portions 99 and the inside wall surfaces of the outer wall portions of the housing 31, the webs or ribs 133 extending for a portion only of the inside length of the housing 96 to form the passages or openings 15 134 between the front edges of the webs or ribs 133 and the wall portions 97, the webs or ribs 133 acting as baffle means for causing the cooling fluid or air, passing into the chamber 104, to flow longitudinally of the webs or ribs 133 and the conical 20 or frusto-conical portion 99 and the cylindrical portion 98, thus causing the cold air to pass over the relatively hottest portions of the housing 96.

It is to be also noted that the housings or 25 members 31 and 96 hereinafter more fully described, may be used without tubular assemblies such as A or B and when incorporated in tubular housings may be installed as heater units in association with muffler conduits and assemblies of 30 conventional design to permit my heater means by itself to be thus installed as accessory means with muffler units of automotive vehicles.

In operation the fluids or gases are expelled 35 from the internal combustion engine or similar unit through the exhaust pipes or conduit 50 and thus into the tubular assembly A and a portion of the fluids or gases will pass directly through the outlet opening in the straight cylindrical portion 5 and into the cone or conical passage 38 and will also further pass directly therethrough 40 into the relatively narrow chamber 87 between the rear end of the housing 31 and the disc member 18 and thus into the tubular assembly B and then through the outlet opening in the straight cylindrical portion 5 of the tubular assembly B 45 directly into and through the outlet pipe or tube 30 and thus to the outside atmosphere.

At the same time a portion of the fluids or gases 50 entering the tubular assembly A will be impeded by the smaller diameter of the outlet opening in the straight cylindrical portion 5 of the tubular assembly A and forced to escape through the rows of louvered perforations 2 and past the hood portions 3 of the tubular assembly A into the chamber 16 from where they will slowly pass 55 through the openings 18 between the inner surface of the flange 14 of the disc member 12 and the hood portions 3 of the tubular assembly A, said fluids or gases thus flowing slowly from the chamber 16 into the chamber 17 and as the fluids or gases issue or escape through the louvered 60 perforations 2 in the chamber 16, they will be caused to whirl, rotate, or tangentially flow adjacent the outside surfaces of the tubular assembly A and adjacent the inside surfaces of the outer tube 4 and this same whirling or turbulent flow will take place in the chamber 17 as the gases or fluids escape from the tubular assembly A through the louvered perforations 2 of the tubular assembly A located within and connecting 65 with the chamber 17.

A portion of the whirling fluids or gases in the chamber 17 will be collected and drawn into and 70 through the conical passage 38 by the high velocity of the fluids and gases passing directly 75

through the nozzle or outlet opening in the substantially straight cylindrical portion 5 of the tubular assembly A and into and through the conical passage 38.

- 5 Also a portion of the gases or fluids in the chamber 17 will flow along the outside surfaces of the housing 31 through the openings 34 formed between the corrugated structure 32 and the inside surface of the outer tube 4 and into the chamber 87 and into the tubular assembly B by the high velocity of the fluids or gases passing through the conical passage 38 and into the tubular assembly 10 B, the fluids or gases which are drawn through the openings 34 and to the chamber 87 passing across and adjacent the end surface of the wall portion 37 between the fins or ribs 40, thus being caused to flow with a whirling or turbulent motion 15 due to the location and position of the fins or ribs 40, the fluids or gases thus passing around and through the housing 31 in concentric paths.

A portion of the fluids or gases which enter the tubular assembly B will flow directly through the 20 outlet opening in the straight cylindrical portion 5 forming the nozzle of the tubular assembly B into and through the exhaust pipe or tube 30 into the atmosphere and a portion of said fluids or gases entering the tubular assembly B will 25 escape through the louvered perforations 2 thereof into the chamber 25 and will pass through the openings 15 between the inner surface of the flange 23 and the hood portions 3 of the louvered perforations 2 of the tubular assembly B into the 30 chamber 26 where they will meet and be turbulently mixed with that portion of the fluids or gases which enter the tubular assembly B and escape through the louvered perforations 2 into the chamber 26 in a similar manner to the flow 35 of the fluids or gases through the tubular assembly A.

The operation of the combined muffler and heater assembly disclosed in Figs. 11 to 19 inclusive is similar in operation to that described 40 above and is further provided with insulating material around its cylindrical or outer surface as well as its ends to insure that the heat from the combined heater and muffler assembly will not be radiated therefrom to cause unwanted 45 heating of the body and occupants of the automotive vehicle in warm weather and also insure that the heat will be retained therein in cold weather to prevent dissipation of the heat and efficient utilization of same for heating the body 50 and occupants of the automotive vehicle.

The disc members 12 and 21 are adapted to be positioned during assembly and before permanent attachment to provide any desired number of rows of louvered perforations 2 for direct connection respectively with the chambers 16 and 60 17 and 25 and 26, this feature of my invention being similar to that disclosed in the above mentioned pending application.

I claim:

- 65 1. In a combined muffler and heater for use with the exhaust conduit of an internal combustion engine, the combination of muffler means provided with an inlet opening for connecting with said exhaust conduit, said muffler means being provided with an outlet opening, and a housing member operatively mounted between said inlet and outlet openings of said muffler means and provided with a cone shaped passage to permit exhaust fluids from said exhaust conduit to pass through said cone shaped passage

5 to said outlet opening of said muffler means, said housing member being provided with a chamber surrounding the walls of said cone shaped passage and adapted to receive a cooling fluid therethrough, the delivery end of said passage being substantially spaced from the outlet of said muffler means.

2. In a combined muffler and heater for use with the exhaust conduit of an internal combustion engine, the combination of muffler means 10 provided with an inlet opening for connecting with said exhaust conduit, said muffler means being provided with an inlet and an outlet opening, and a housing member operatively mounted between said inlet and outlet openings of said 15 muffler means and provided with a cone shaped passage to permit exhaust fluids from said exhaust conduit to pass through said cone shaped passage to said outlet opening of said muffler means, said housing member being provided with a chamber surrounding the walls of said cone shaped passage and adapted to receive a cooling fluid therethrough, said housing member being further provided with fins arranged longitudinally on its end wall portions relative to the 20 outlet opening of said cone shaped passage, to cause said exhaust fluids flowing around said housing member to flow toward the central portion of said muffler means, on the way to said outlet opening of said muffler means with a 25 whirling motion.

3. In a combined muffler and heater, the combination of muffler means for receiving exhaust fluids therethrough, said muffler means being provided with a tubular housing, and a housing 30 member provided with a cone shaped passage to permit said exhaust fluids to flow therethrough when flowing through said muffler means, said housing member being provided with a chamber surrounding said cone shaped passage for receiving a cooling fluid therethrough, said housing member being provided with a corrugated wall structure for extending within and engaging the inner surface of said tubular housing, said corrugated wall structure forming, with the 35 walls of said tubular housing, passages extending longitudinally adjacent said housing member to allow a portion of said exhaust fluids received into said muffler means to flow around said housing member, said housing member being further provided with fins arranged tangentially around the outlet opening of said cone shaped passage to cause said exhaust fluids flowing around said housing member to flow toward the central portion of said muffler means with a 40 whirling motion.

4. In a combined muffler and heater for connection with the exhaust conduit of an internal combustion engine and with a compartment to be heated, the combination of a tubular member 45 provided with an outlet, together with a compartment between its ends, said compartment being provided with an outlet, a second tubular member mounted within said first mentioned tubular member and providing an inlet therefor 50 to receive fluids flowing from said exhaust conduit, said second tubular member having a partially closed end extending within said compartment of said first mentioned tubular member, said second tubular member being provided with 55 one or more rows of louvered perforations to cause exhaust fluids flowing from said exhaust conduit into said second tubular member to flow tangentially through said louvered perforations into and around said compartment, a housing 60

member mounted in said compartment of said first mentioned tubular member and providing a chamber at the front and rear ends of said housing member within said compartment, said 5 housing member being provided with a cone shaped passage for receiving therethrough fluids flowing out of said partially closed end of said second tubular member, said housing member being provided with corrugated wall portions for 10 forming, together with the outer wall portions of said first mentioned tubular member, passages for the flow of exhaust fluids from said chamber, within said compartment and at the front end of said housing member, to said chamber 15 within said compartment and at the rear end of said housing member, said housing member being further provided with fins on its rear wall portion and arranged tangentially around the opening of said cone shaped passage to cause 20 exhaust fluids entering into said chamber, at the rear end of said housing, from said passages, formed by said corrugated wall portions of said housing member together with the outer wall portions of said first mentioned tubular member, 25 to flow with a whirling motion toward and into said outlet of said compartment of said first mentioned tubular member, a third tubular member connected with said outlet of said compartment of said first mentioned tubular member 30 and provided with a partially closed end adapted to guide fluids flowing therethrough into said first mentioned outlet of said first mentioned tubular member, said third tubular member being provided with one or more rows of louvered perforations to cause exhaust fluids flowing into said 35 third tubular member to flow tangentially through said louvered perforations and around said third tubular member to join with the exhaust fluids flowing into and through said outlet of said first mentioned tubular member, and means for guiding said cooling fluid, after it has been heated, into said compartment of the vehicle.

5. In a combined muffler and heater, the combination of a housing means, a heater member mounted in said housing means and provided with a passage therethrough, said passage having a cylindrical portion connected to a relatively smaller outlet portion by a conical portion, said 40 heater member being provided with a chamber around said cylindrical and said conical portions and adapted to receive a cooling fluid therethrough, said heater housing being provided with a corrugated structure forming, with said housing means, passages connected with said cylindrical portion of said passage through said heater member and with said outlet portion, means for 45 guiding a flow of cool air into said chamber of said heater member, a second means for guiding a flow of heated air from said chamber of said heater member, and a muffler means suitably

supported and extending within said cylindrical portion of said passage through said heater member, said muffler means being provided with inlet and outlet openings, said muffler means being provided with apertures arranged circumferentially therearound for discharging exhaust gases against said cylindrical portion of said passage extending through said heater member. 5

6. In a muffler, a compartmented housing, an inlet conduit projecting substantially into said housing, said conduit having vents thru the walls thereof, a chamber into which a portion of the gases flowing through said conduit are released, a converging passage at the end of said conduit with the large end thereof being of substantially 10 greater diameter than the end of said conduit, the end of said conduit being of restricted shape whereby the gases passing therethrough are given high velocity thereby inducing increased flow of the gases from said chamber, a plurality of 15 individual gas passes in said housing exteriorly of said passage leading from said chamber, a second expansion chamber at the small end of said passage, an outlet conduit from said housing, and a second conduit coaxial with said passage residing within said second chamber and having vents through the walls thereof open to said second chamber, the delivery end of said second conduit being spaced from said outlet conduit and of restricted diameter thereby 20 inducing a flow of gases from said second chamber. 25

7. In a muffler, a compartmented housing, an inlet conduit projecting substantially into said housing, said conduit having hooded vents therethrough, a chamber around said conduit into 30 which a portion of said gases flow, said hooded vents lending a circular motion about said conduit to said gases, a converging passage at the end of said conduit with the large end thereof being of substantially greater diameter than the 35 end of said conduit, the end of said conduit being of restricted shape whereby the gases passing therethrough are given high velocity thereby inducing increased flow of the gases from said chamber, a plurality of individual gas passes in 40 said housing exteriorly of said passage leading from said chamber, a second expansion chamber at the small end of said passage, an outlet conduit from said housing, and a second conduit coaxial with said passage residing wholly within 45 said second chamber and having hooded vents through the walls thereof open to said second chamber, said hooded vents being curved to impart a rotary motion to the gases entering said second conduit from said second chamber, the 50 delivery end of said second conduit being spaced from said outlet conduit and of restricted diameter thereby inducing a flow of gases from said second chamber directly through said outlet conduit. 55
